INVENTOR

Andrew J. Knight,
By Owen Bond Crampton,
his attorney.

UNITED STATES PATENT OFFICE.

ANDREW J. KNIGHT, OF TOLEDO, OHIO.

OIL-BURNER.

1,391,481.

Specification of Letters Patent. Patented Sept. 20, 1921.

Application filed November 11, 1920. Serial No. 423,218.

To all whom it may concern:

Be it known that I, ANDREW J. KNIGHT, a citizen of the United States, and a resident of Toledo, in the county of Lucas and State 5 of Ohio, have made an Invention Appertaining to Oil-Burners; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this specification.

15 This invention relates to burners and particularly to those adapted for burning kerosene and other hydrocarbon oils as a fuel.

The object of my invention is the provision of a simple and improved burner of the 20 character described which is simple and inexpensive in its construction and adapted to generate a liquid fuel into a highly inflammable gas, and is also adapted to use either a natural or artificial gas or gas generated 25 from a hydrocarbon oil or both together, as desired.

The invention is fully described in the 30 following specification, and while, in its broader aspect, it is capable of embodiment in numerous forms, a preferred embodiment thereof is illustrated in the accompanying drawings, in which,—

Figure 1 is a central vertical longitudinal section of a burner embodying the invention, 35 and Fig. 2 is a top plan view thereof.

Referring to the drawings, 1 designates a 40 hollow burner body, in the present instance, of conical form and closed at its top by a perforated or slotted burner plate 2 through which the gas from the interior of the burner is discharged. The burner 1 is provided at 45 its lower end with a laterally extending hollow neck portion 3 having an open outer end.

A conical deflector 4 is mounted centrally 50 on the burner top 2 with its side wall extending outward and upward in overhanging relation to the burner top openings to effect an outward deflection of the flame rising from the burner. The deflector is provided in its wall adjacent to its outer edge with a

gas generating passage 5 of spiral form with its lower end connected to a supply pipe 6 having communication with any suitable source of hydrocarbon oil supply and with its upper end connected with a pipe 7 for 55 carrying away the generated gas. The pipe 7 extends down through the burner 1 and neck 3 and is provided without the outer end of the latter with an ejector nozzle 8, by which the generated gas may be directed into 60 the hollow neck 3. A pipe 9 having valve controlled communication with a source of natural or artificial gas supply, is tapped into the nozzle 8 so that such nozzle may be supplied either with gas generated in the 65 deflector 4 from hydrocarbon oil supplied thereto, or with gas from the pipe 9, or from both together, as may be desired. Gas from the pipe 9 is used in starting the burner and until the deflector 4 has become sufficiently 70 heated to generate gas from the oil supplied thereto.

I wish it understood that my invention is not limited to any specific construction, arrangement or form of the parts, as it is 75 capable of numerous modifications and changes without departing from the spirit of the claim.

Having thus described my invention, what I claim as new and desire to secure by Letters Patent, is,—

A burner of the class described, comprising a burner body having gas discharge openings in its top and having a hollow laterally extending neck portion open at its 85 outer end, a conical deflector mounted on the burner top and having a gas generating passage therein in communication at one end with a source of hydrocarbon oil supply, a pipe leading from the other end of the generating passage through the burner and neck 90 thereof adjacent to its outer end, an ejector nozzle connected to the outer end of the pipe in position to discharge gas therefrom into the burner neck, and a valve controlled 95 pipe opening communication between the nozzle and a source of gas supply.

In testimony whereof, I have hereunto signed my name to his specification.

ANDREW J. KNIGHT.
